FRITZ POHL, OF VIENNA, AUSTRIA, AND MAX VOGEL, OF FRANKFORT-ON-THE-MAIN, GERMANY, ASSIGNEES TO THE FIRM M. VOGEL A. G., GESCHAFTSBÜCHER- UND METALLWAREN-FABRIK, OF FRANKFORT-ON-THE-MAIN, GERMANY

CLAMPING DEVICE FOR FILES, NEWSPAPER HOLDERS, AND THE LIKE

Application filed January 31, 1929, Serial No. 336,588, and in Germany April 10, 1928.

This invention relates to a clamping device for holding nonperforated papers in files or newspaper holders and the like. The resilient clamping element, adapted to be lifted or lowered and acting upon the paper, is held in the clamping position by means of a slide, guided in the direction of the hinge-bolt of the two clamping elements and having tightening surfaces. Owing to this construction a clamping effect is obtained which is more accurately adjustable and more reliable than in the commonly used devices.

An embodiment of the invention is illustrated by way of example in the accompanying drawing in which:

Fig. 1 shows a form of construction of the clamping device in cross-section and in the inoperative position.

Fig. 2 is a similar view as Fig. 1, the clamping element being lowered but not yet operative.

Fig. 3 is a top plan view of Fig. 2.

Fig. 4 is a similar cross section as Fig. 2, the clamping element or tightening faces being in the operative position.

Fig. 5 is a top plan view of Fig. 4.

Fig. 6 shows the clamping device in front elevation, the tightening faces being still in the inoperative position.

Fig. 7 shows a clamping device of modified construction in cross section in the open position.

Fig. 8 is a similar view as Fig. 7, the clamping element being tightened.

Fig. 9 shows another modification of the clamping device, the clamping element being shown in cross section in the operative position.

Fig. 10 is a top plan view of Fig. 9.

Fig. 11 shows in cross section the clamping device, the clamping element of which is in the inoperative position, and a braking device which is provided.

Fig. 12 is a side elevation of Fig. 11.

The clamping device consists of a base plate 1, to be fixed on the file or on a newspaper holder, of a movable clamping element 2 adapted to be oscillated 90° and of a locking slide 3 having tightening faces. The

narrow base plate 1 has its right longitudinal edge 4 slightly bent upward to better hold the clamped papers. The base plate 1 has on the left longitudinal edge on each end of the same an upwardly bent flap 5 and at the middle an extension 6 (Figs. 3, 5 and 6), the semicircular transverse edges of which are bent upward to form bearing flaps 7, for a bolt 8. On this bolt 8 the downwardly bent flaps 9 of the clamping element 2 are rotatably mounted between the bearing flaps 7.

The clamping element 2 has on its lower side a slightly curved spring blade 10, extending in the longitudinal direction of the base plate 1, the ends of said spring blade pressing against the papers when the clamping element 2 is lowered.

The base plate 1 is fixed on the inner side of the file for example by small rivets or the like, and it has with this object in view two rivet holes 11 (Fig. 3).

The locking slide 3 consists of half a sleeve, the longitudinal edges of which form two pairs of wedge faces 12, 12' and 13, 13' (Fig. 5) extending behind each other. The locking slide 3 is guided in curved slots 14, 15 (Fig. 1) of the flaps 9, 7. The length of these curved slots 14, 15 is selected so that, when the locking slide 3 is pressed in, the wedge faces 12, 13 arranged the one behind the other bear against the ends of the slots in the stationary flaps 7 and the other wedge faces 12', 13' bear against the ends of the slots in the movable flaps 9.

The lowered clamping element 2 with the blade spring 10 is at the pushing in of the locking slide 3 pressed continually more strongly against the base plate 1, so that the clamped papers are securely held. Owing to the feeble pitch of the wedge faces (which for clearness sake are shown in the drawing in a larger than the natural scale) automatic loosening of the clamping element 2 is absolutely prevented.

The clamping device shown in Figs. 7 and 8 is distinguished by a specially simple construction and low height. In this form of construction curved slots 14 are provided only in the stationary flaps 7 of the base plate 1.

When the locking slide 3 is being pushed

in, the wedge faces 12 are supported by the ends of the curved slots 14, the wedge faces 12' acting upon the abutment faces 15' of the flaps 9 whereby the blade spring 10 of the clamping element 2 is strongly and securely pressed against the base plate.

In order that the locking slide 3 may be more effectively locked in any actual position a braking device is provided in the form 10 of construction shown in Figs. 9 to 12. This braking device consists preferably of a spiral spring 16, the end 17 of which is fixed on the base plate 1, the other end 18 pressing against the inner edge of the clamping element 2 so that this clamping element is automatically 15 lifted by the spring 16 when the locking slide 3 is being pulled out.

In the clamping device shown in Figs. 9 and 10, the portion 8' of the axle 8 situated 20 between the bearing flaps 9 of the clamping element 2 is of such diameter that the spiral spring 16 wound around this portion bears against the inner surface of the locking slide 3. The spiral spring 16 exerts therefore a 25 braking action opposing a longitudinal shifting of the locking slide so that this locking slide is better secured in its actual position and more effectively secured against accidental shifting.

30 In order to avoid the great diameter of the spiral spring 16 the following arrangement is made according to Figs. 11 and 12.

The axle 8 is of small diameter and not fixed by rivets in the outer bearing flaps 7 of 35 the base plate 1 but shiftably mounted in all four bearing flaps 7, 9, its two ends being journaled in cup-shaped handles 19 of the locking slide 3 so that, when this locking slide is being shifted, the axle 8 is shifted 40 also. The spiral spring 16 tightly wound around the bolt 8 exerts therefore at longitudinal shifting of the locking slide a braking action upon this slide so that the clamping element 2 is sufficiently secured in any 45 position against accidental lifting. This braking effect of the spiral spring 16 is still further increased by the friction of the axle 8 in the holes of the bearing flaps 7, 9.

This form of construction presents the advantage that riveting of the axle 8 is not required. A further advantage is that the locking slide 3 which, owing to its tapering shape, is weakened at the middle is secured by the 50 axle 8 against bending.

55 We claim:—

1. A clamping device, specially designed for files, newspaper holders and the like, comprising in combination a yieldable clamping element adapted to be lowered 60 upon the papers and to be raised from the same, an axle of said clamping element, a base plate in the file supporting the axle of said clamping element and a locking slide 65 having wedge faces shiftable along said axle

to secure said clamping element in the locking position.

2. A clamping device specially designed for files, newspaper holders and the like, comprising in combination a base plate fixed 70 in the file, a lateral extension at one long side of said base plate, flaps formed by the upwardly turned ends of said extension having each a curved slot, an axle journaled in said flaps, a clamping element on said axle, two downwardly directed flanges at the ends of said clamping element having each a curved slot, a locking slide in the shape of a half sleeve guided in said curved slots in 75 said four flaps and having edges composed each of two offset wedge faces designed to bear those of the one set against the ends of the curved slots in the flaps of the base plate and those of the other set against the ends of the curved slots in the flaps of said 80 clamping element.

3. A clamping device as specified in claim 1, comprising in combination with the locking slide, a braking device adapted to lock 85 said slide against accidental shifting.

4. A clamping device as specified in claim 1, comprising in combination with the axle, the clamping element and with the locking slide, a spiral spring wound around said 90 axle adapted to brake said slide by friction and bearing against said clamping element to automatically lift the same when it is released by said locking slide.

5. A clamping device specially designed for files, newspaper holders and the like, comprising in combination a base plate fixed 100 in the file, a lateral extension at one long side of said base plate, flaps formed by the upwardly turned ends of said extension having each a curved slot, an axle extending through said flaps, a clamping element on said axle, two downwardly directed flanges at the ends of said clamping element having each a curved slot, a locking slide in the 105 shape of a half sleeve guided in said curved slots in said four flaps and having edges composed each of two offset wedge faces designed to bear those of the one set against the ends of the curved slots in the flaps of the base plate and those of the other set against the 110 ends of the curved slots in the flaps of said clamping element, a cup-shaped handle at each end of said locking slide in which said axle of said clamping element is fixed, and a spiral spring tightly wound on said axle 115 adapted to secure said locking slide against accidental shifting owing to the friction between said spring and said axle and between said axle and the holes in the flaps through which said axle extends.

In testimony whereof we affix our signatures.

MAX VOGEL.
